UNITED STATES PATENT OFFICE.

GUSTAVUS W. ANDERSON AND ANDREW J. ANDERSON, OF GALESBURG, ILLINOIS.

COMBINED SHADE-ROLLER HOLDER AND CURTAIN-POLE BRACKET.

1,040,487.

Specification of Letters Patent.

Patented Oct. 8, 1912.

Application filed January 15, 1912. Serial No. 671,369.

To all whom it may concern:

Be it known that we, GUSTAVUS W. ANDERSON and ANDREW J. ANDERSON, citizens of the United States, and residents of Galesburg, in the county of Knox and State of Illinois, have jointly invented a new and useful Combined Shade-Roller Holder and Curtain-Pole Bracket, of which the following is a specification.

10 Our present invention relates to devices for sustaining window - shade - rollers and curtain-pole brackets.

The principal end and object of the invention is to improve the construction and 15 increase the capacity, utility and efficiency of devices of this character and type.

Another object is to so construct, and to so modify the general construction of the improvements that they are readily applicable to either the window casing or the 20 sash-strip.

Inasmuch as shade-rollers and curtain-poles or rods are frequently taken from place to place, and that window casings vary 25 greatly in width, it is a prime factor that allowance be made whereby such rollers and rods may be employed on presecured means for sustaining them, without changing their positions and thus marring the casing or 30 the strips.

To provide a device capable of such allowances is an object.

That the device be small, unobtrusive and inconspicuous in appearance, and adapted 35 for use on the narrowest sash strip, is a desirable feature or quality, and to provide one possessing such constitutes a further object.

That the placement of the curtain-bracket 40 be variable or selective with reference to the strip or casing is desirable; to provide a device in which the bracket is novelly movable in and with reference to the holder-parts is an essential object.

45 To the attainment of these and other ends and objects the invention consists in the constructions, combinations and modifications hereinafter described and pointed out in the appended claims.

50 In the accompanying drawings: Figure 1 is a top plan of the parts constituting the principal and a modified form of the left hand ones of our improvements, shown as applied respectively to a window casing and a sash strip; the casing shown in fragmental section; Fig. 2, a detail, front elevation of

the base member shown as applied to the casing in Fig. 1; Fig. 3, a detail, a side elevation of either of the left-hand-side lock-members or shade-roller supporting brackets shown in Fig. 1; Fig. 4, a detail, a front elevation of the base member which is applied to the sash-strip; Fig. 5, a detail of the member which receives—in a transversely arranged eye—the revolving pintle of the shade-roller, and which is arranged at the right hand side of the window; Fig. 6, a detail, seen from the side, of the curtain-supporting bracket; and Fig. 7, a modification, a fragment of the socket portion of either shade-roller-bracket.

Inasmuch as the respective elements, excepting only the member 9 hereinafter referred to, are reversible, in order that by turning them upside down they will serve 75 at either the right or left hand side of the window, we shall herein describe but one of each of said elements.

Coming now to a detailed description of the drawings and referring thereto by numbers, the same one of which indicates the same or a corresponding part in the several figures, 2 indicates the preferred form of base-member and consists of a casing-engaging portion 3 from the face of which is a 85 projection 4 having an eye 5 and from the inner side of which projects a spur 6. The upper and lower faces of the projection 4 are each provided with a channel 7.

9 indicates a substantially L-shaped pin-locking bracket, one arm of which constitutes a socket 10 adapted to slide loosely on the spur 6. 11 is a threaded recess in the sleeve 10, and 12 is a set-screw threaded therein and adapted to lock the member 9 90 in selective positions on said spur. The other, or outstanding arm is provided with the usual pin-receiving slot 13, and on its side is provided with a curtain-bracket-receiving eye 14. In the process of manufacture we have found it convenient to provide the socket 10 with a slot 30, the presence or the absence of which is optional.

15—the modified form—is a sash-strip fixture comprising a base 3 provided on its 105 face with a projection 4 from which projects a spur 6. An eye 5 is provided in the projection and corresponds to the similarly numbered eye in the projection shown in Fig. 2.

16 indicates the pintle-receiving bracket of either the principal or the modified form,

and comprises a socket portion 10 and a projecting arm 19, the latter provided with the usual transversely arranged pintle-receiving eye 20 and on its side with a vertically arranged curtain-bracket-receiving eye 14.

Each base 3 is provided with countersunk screw-holes 21 which receive wood-screws 22, the threads of which engage the casing 23 or sash-strip 24 in the usual manner.

10 25 is a curtain-pole bracket, preferably formed of a single wire having disposed angularly to its body 26 a downwardly extending arm 27 adapted for engagement with the eye 5 in the projection 4 or with the eye 14 on the bracket 9, and has a curtain-rod-sustaining bow portion 28 at its outer end. If the curtain rod be provided with apertures, as is frequently the case, the free ends of the brackets 25 may be inserted thereinto 15 and more securely held than if the rod were laid loosely in said bow.

If a shade-roller be not of the proper length to fit into the notch 13 and eye 10 of a pre-hung pair of brackets, either or 20 both of the members 9 or 16 may be slid along the spur or spurs 6 to the proper position and there securely held by tightening the set-screw 12. If it is desired to hold the curtain closely to the window the 25 bracket arms 27 are to be loosely inserted in the eyes 5; and if it be desired to hang it a greater distance therefrom the placement 30 will be in the eyes 14 in the pin and pintle-receiving members. The body portion of 35 the arms 27 rest in that channel which is uppermost, and are held from swinging movement thereby. In use, the bows 28 may stand either inwardly or outwardly, as desired—in fact, they are reversible and interchangeable in order to so make them, but it is preferred that they stand wide in order 40 that the curtains may cover and to some extent obscure the shades from sight.

Numerous unessential changes will at once 45 suggest themselves to one skilled in this art. We have not deemed it either necessary or best, however, to encumber this specification and the accompanying drawings with descriptions and illustrations of such.

50 Therefore, without limiting ourselves to particular details of construction we claim as our invention the following, to-wit:—

1. In a device of the character described, a 55 pair of bases each of which is provided with an eye, a pair of shade-roller brackets engaged therewith and each having an eye, and a pair of curtain-rod supporting brackets adapted for engagements with said eyes as pairs.

60 2. In a device of the character described, a

pair of bases each of which is provided with an eye, a pair of shade-roller brackets slidably engaged therewith and each having an eye, and a pair of curtain-rod supporting brackets adapted for engagements with said 65 eyes as pairs.

3. In a device of the character described, a pair of bases each of which is provided with a spur and an eye, a pair of shade-roller brackets slidably engaged with said spur 70 and each having an eye, and a pair of curtain-rod supporting brackets adapted for engagements with said eyes as pairs.

10 4. A device of the character described comprising a pair of bases, a shade-roller 75 bracket slidably mounted on each thereof, and a curtain-supporting bracket adapted for engagements with either the bases or brackets.

5. A device of the character described 80 comprising base elements, shade-roller-supporting brackets adapted for selective positions thereon, and curtain-rod supporting brackets adapted for engagement with either said base elements or said brackets. 85

6. In a device of the character described, a base element provided with a projection having a channel in both its upper and lower faces and having also a bracket-receiving eye, said projection provided with a 90 spur, a shade-roller supporting bracket provided with a bracket-receiving eye, said bracket slidably mounted on said spur, means for locking it thereon, and a curtain-rod supporting bracket adapted for engagement with either of said eyes and its main 95 portion to rest in one of said channels.

7. A device of the character described including a base element provided with a projection having a channel in both its upper 100 and lower faces and an eye, and provided also with a spur, a shade-roller-supporting bracket provided with a socket adapted to receive said spur, said bracket provided also with a threaded aperture and a curtain- 105 bracket-receiving eye, a set-screw threaded in said aperture and adapted to contact said spur, and a curtain-rod-supporting bracket adapted for engagement with either of said eyes and its body portion supported in the 110 upper one of said channels.

In witness whereof we hereunto set our hands at Galesburg, in the county of Knox and State of Illinois, this 11th day of January, 1912.

GUSTAVUS W. ANDERSON.
ANDREW J. ANDERSON.
